THERMIONIC VACUUM TUBE CIRCUIT

Paul Baker, Los Angeles, Calif., assignor to
Robert A. Casey, Los Angeles, Calif.

Application March 11, 1935, Serial No. 10,454

7 Claims. (Cl. 179—1)

This invention relates broadly to vacuum tube circuits employing heater type tubes in which the cathodes of the tubes are not heated directly by the passage of current therethrough but instead 5 are raised to electron emitting temperature by heat conducted and/or radiated from a separate electrically heated element positioned adjacent thereto.

It is characteristic of heater type tubes that 10 there is a substantial time lag following application of current to the heater element before the cathode attains electron emitting temperature and becomes operative. This lag is objectionable in many devices, such as radio sets and intercom- 15 municating telephone apparatus for example, because the user must wait for the tubes to heat before he can use the device. It is also objectionable because in many circuits excessive plate potential is applied to the tubes by the power 20 supply system while the tubes are heating, due to the fact that the tubes draw little or no plate current during the heating period.

A broad object of the present invention is to reduce the time lag referred to in devices employing heater type tubes.

A feature of the invention is a circuit for A. C. 25 operated vacuum tube amplifiers and the like which at all times supplies a small amount of current to the heater elements of the tubes to preheat them and yet does not involve expensive, delicate or unreliable control apparatus and does not draw excessive energy from the line.

In essence, my circuits constituting the present 30 invention differ from prior circuits known to me in that they include a means for delivering a reduced current to the heater elements of the tubes during inactive periods while at the same time preventing wastage of current in other portions of the circuit.

40 Thus it is present practice in vacuum tube amplifying devices adapted to be completely energized by alternating current from a light socket to provide in the device a power transformer having a primary winding adapted to be connected to the light socket, a low potential 45 secondary winding or windings connected to the heater elements of the tubes, a high potential secondary winding for supplying current to a plate current supply system, including a vacuum 50 tube rectifier having a filamentary cathode, and a low potential secondary winding for supplying low potential alternating current to the rectifier filament; the device being turned on and off by simply making and breaking the power supply 55 connection to the primary winding of the trans-

former. Such a device, if modified in accordance with my invention, would include a current limiting device for limiting the potential applied by the first mentioned secondary winding to the heater elements of the tubes, with a switching 5 device operable into "on" and "off" positions for applying reduced potential to the heater elements and opening the rectifier filament circuit when the switch is in "off" position and applying full 10 potential to the heater elements and completing 10 the rectifier filament circuit when the switch is in "on" position.

I am aware that it is old to condition vacuum 15 tubes for instant use by applying reduced current to the cathode heater elements during inactive periods and I am also aware that this reduced current has been obtained by reducing the potentials developed in the secondary windings of the power transformer. The practice of reducing the 20 potentials developed in the secondary windings of the transformer is unsatisfactory, however, in the circuits employing a hot cathode rectifier energized from the same transformer as the heater elements for the reason that when the 25 potential applied to the heater elements is reduced to the proper value to maintain the cathodes of the heater type tubes at a suitable temperature, slightly below their emission temperature, the directly heated cathode of the rectifier tube will be heated sufficiently to still emit electrons, thereby producing an entirely unnecessary 30 current drain not only from the low potential secondary winding supplying the rectifier filament but also from the high potential secondary winding supplying current to be rectified. I have 35 also found that rectifier filaments in such a circuit have their lives very much reduced. My circuit, on the other hand, eliminates wastage of 40 current, since no current whatever is drawn from the low potential filament heating winding and the high potential winding supplying current to be rectified.

45 For purposes of illustration, the invention is disclosed as incorporated in an intercommunicating telephone system employing a vacuum tube amplifier. A full understanding of the invention, together with other objects and features thereof not heretofore mentioned, may be had from the following detailed description which refers to the drawing.

50 In the drawing:

Fig. 1 is a schematic circuit diagram of an intercommunicating telephone system incorporating the invention;

Fig. 2 is a detail schematic diagram illustrat- 55

ing a modification of the circuit shown in Fig. 1; and

Fig. 3 is a detail schematic diagram illustrating still another modification of the circuit shown in Fig. 1.

Referring to Fig. 1, I have shown two telephones 1 and 2, respectively, adapted to be interconnected through a vacuum tube amplifier, with control switches for energizing and deenergizing the amplifier and reversing the direction of communication. The telephones 1 and 2 may be of any conventional form, although I prefer to employ as these units dynamic speakers of the permanent magnet type, in which no external source of current is required to energize the field in which the moving coil attached to the diaphragm is suspended. Inasmuch as this particular type of telephone unit is not essential, it has not been illustrated in detail, the construction of such devices being well known.

The amplifier disclosed is a three-stage unit containing three tubes 3, 4 and 5, respectively, of the heater type, each tube containing a cathode 6 adapted to be heated by conduction and/or radiation from a heater element 7, a grid 8 and anode 9. The grid of the first tube 3 is connected to one end of the secondary winding of an input transformer 10, the other end of which winding is connected to ground through a ground conductor 11. A variable resistance 12 is shown connected in shunt across the secondary winding of input winding 10 for volume control purposes although if desired any other known method of varying the potential applied to the grid of the first tube may be employed. The cathode 6 of each of the tubes 3, 4 and 5 is connected to the ground conductor 11 through a grid biasing resistor 13 shunted by a by-pass conductor 14. The amplifier is of the resistance coupled type, the anode of the first tube 3 being connected to a source of anode potential through a resistor 16 and coupled to the grid of tube 4 through a coupling condenser 15. Likewise the anode of tube 4 is connected to the source of anode potential through a resistor 18 and to the grid of tube 4 through a coupling condenser 15, and the grids of both tubes 4 and 5 are connected to the ground conductor 11 through leak resistances 16. The anode of the last tube 5 is connected through the primary winding of an output transformer 17 to the source of anode potential.

The amplifier so far described is of well known construction and may be varied in design without producing any effect insofar as the present invention is concerned. It is adapted to be energized by supplying alternating current of suitable potential to the heater elements 7 of the tubes and supplying constant potential of suitable value to the various leads 18, 19 and 20 connected to the anodes of the three tubes. To supply these various potentials, a power supply unit is provided, preferably as an integral part of the amplifier.

The power supply unit comprises as its essential elements a power transformer 21, a hot cathode rectifier tube 22, and a filter 23. The power transformer 21 has a primary winding 24 adapted to be connected through an impedance element 25 directly to a suitable source of alternating current of constant voltage, such as a 110-volt lighting circuit. The transformer 21 is also provided with a low potential secondary winding 26 which is permanently connected through leads 27 and 28 to the heater elements 7 of the three tubes, a high potential secondary winding 29 having a mid tap 30 connected to the ground con-

ductor 11 and having its opposite ends connected through leads 31 and 32, respectively, to the two anodes of a full wave rectifier tube 22, and a third low potential secondary winding 33 adapted to be connected through a contact 34 and armature 35 of a relay 36 to the filament of the rectifier tube 22. The filament circuit of the rectifier tube is also connected by a lead 31 through a resistor 32 to the high potential side of the filter 23, this filter comprising a reactance 39 and resistance elements 40 and 41, all connected in series, and with condensers 42 connected between ground and the terminals of the reactance 39 and resistors 40 and 41. The resistors 40 and 41 serve not only to filter the current flowing therethrough but to reduce its potential to suitable values for the tubes 3 and 4. Thus the anode supply conductor 18 for tube 5 is connected directly between reactance 39 and resistor 40, the anode supply conductor 19 for tube 4 is connected between the resistors 40 and 41, and the anode supply conductor 18 for tube 3 is connected to the end of resistor 41. A potentiometer 43 is also provided, connected across the first condenser 42 of the filter circuit for supplying a direct current to operate a communication reversing relay 44. Thus the winding of relay 44 is connected in series, through a lead 45, between a tap 46 on potentiometer 43 and one contact 47 of a switch 48 having a cooperating contact 49 connected to the ground conductor 11. Relay 44 is provided with a pair of armatures 50 and 51, respectively, cooperating with front contacts 52 and 53, respectively, and back contacts 54 and 55, respectively. The front contact 52 and the back contact 55 are connected together and to one terminal of the telephone 1, the other terminal of which is grounded. Similarly, the front contact 54 and back contact 53 are connected together and to one terminal of the telephone 2, the other terminal of which is adapted to be connected through a lead 56 and switch contacts 57 and 58, respectively, to ground.

The impedance element 25 connected in series with the primary winding 24 of the power transformer 21 has its two ends connected to an armature 59 and associated front contact 60 on relay 36. Relay 36 is adapted to be operated by alternating current and has one end of its winding connected through the secondary winding of a transformer 61 to ground and the other end of its winding connected through a lead 62 to a contact 63 on switch 64. Contact 63 is adapted to be connected, when the switch 64 is thrown into "on" position, to a contact 65 connected to ground. As shown in the drawing, switch 64 is in "off" position. The primary winding of the transformer 61 for supplying current to energize relay 36 is permanently connected to the 110-volt A. C. supply line, as shown.

As shown in Fig. 1, the system is in idle condition and the impedance element 25 limits the potential across the primary winding 24 and the potentials developed in the secondary windings 26, 29 and 33 to values substantially below their normal values, depending upon the resistances of the various elements in the system. The impedance 25 is preferably chosen of such a value, with reference to the values of the other elements of the system, that it limits the potential applied by the winding 26 to the heater elements 7 of the amplifier tubes to a value sufficient to maintain the cathodes 6 of the tubes just slightly below the temperature at which they emit electrons. During idle condition no current is drawn from

windings 29 and 33 for the reason that the circuit of winding 33 is open at contacts 34 and 35 on relay 36 and the filaments of the rectifier tube 22 are cold, thereby preventing any flow of space current through the rectifier tube. It will be observed, therefore, that the only electrical power used under idle condition is that consumed in the heater elements 7 of the amplifier tubes and in the impedance element 25. In order to prevent unnecessary losses in the impedance element 25, it is desirable that this impedance constitute a reactance or choke coil. However, in many instances where initial cost is of more importance than operating cost, the impedance element 25 may be constituted by a resistor.

Assuming that it is desired to place the system in operation, the switch 64 is thrown into "on" position, in which contact 57 closes on contact 58, and contact 63 closes on contact 65. Closure of contacts 57 and 58 completes a circuit from ground through contacts 58 and 57, conductor 56, telephone 2, back contact 53, and armature 51 of relay 44, through the secondary winding of the output transformer 17, back to ground on conductor 11. A circuit was previously completed from ground to the telephone 1, back contact 52 and armature 50 of relay 44, through the primary winding of the input transformer 10 to ground on conductor 11. Therefore, the telephone 1 will be conditioned to transmit and the telephone 2 conditioned to receive as soon as the amplifier is energized.

Energization of the amplifier is caused by the closure of contacts 63 and 65 on switch 64. Thus the closure of contacts 63 and 65 completes a circuit from ground through lead 62, the winding of relay 36, and the secondary winding of the transformer 61 back to ground. Relay 36 thereupon pulls up, closing contacts 34 and 35 to connect the filament of the rectifier tube 22 to the secondary winding 33 of the power transformer, and closing contacts 59 and 60 to shunt out the impedance element 25 and apply full line potential to the primary winding 34 of the power transformer. The increase in the potential applied to the primary winding 34 correspondingly increases the potential developed in the secondary windings 26, 29 and 33, the increased potential from winding 26 bringing the heater elements 7 of the tubes up to full heat and also immediately raising the associated cathodes 6 to full electron emitting temperature, and the winding 29 supplying full potential to the rectifier 22, thereby supplying full plate potential to the amplifier tubes.

The system disclosed is adapted for communication in only one direction at one time. However, the direction of communication may be reversed, under the control of the user of the telephone 2, by simply actuating the reversing switch 48 to close contacts 47 and 49. Closure of these contacts supplies current from the rectifier through the potentiometer 43 and the lead 45, through the winding of relay 44, and through lead 66, contacts 47 and 49 of relay 48, back to the ground conductor 11, which constitutes the other side of the rectifier circuit. Relay 44 thereupon pulls, breaking the armatures 50 and 51 from their back contacts 52 and 53, respectively, and connecting them with their front contacts 54 and 55, respectively, thereby connecting the telephone 2 to the primary winding of the input transformer 10 on the amplifier and connecting the telephone 1 to the secondary winding of the output transformer 17 of the amplifier. The user of the telephone 2 may

again reverse the direction of communication by opening the switch 48, thereby releasing relay 44 and restoring the circuits to their original condition as shown in the drawing.

A communicating system of the type shown is very sensitive to disturbances in the tube supply and switching circuits. To prevent undesirable clicks in the telephones at the time the switch 48 is opened or closed, a condenser 67 is shunted across the contacts 47 and 49. The use of the potentiometer 43 limits variations in the potential applied to the anodes of the tubes in the amplifier when the connection to relay 44 is made or broken and also aids in preventing arcing or sparking at the contacts 47 and 49 and the resultant disturbances in the telephones.

When the conversation is finished, the system is restored to idle condition by throwing the switch 64 into "off" position (the position shown in Fig. 1). The breaking of the connection between contacts 63 and 65 opens the actuating circuit for relay 36, thereby opening the contacts of that relay and breaking the filament circuit of the rectifier and restoring the current limiting impedance element 45 in series connection with the primary winding 25 of the transformer, thereby reducing the potential applied to the heater elements 7 to the low value required to maintain the cathodes at a sub-normal temperature. As a result of the fact that the cathodes 6 of the amplifier tubes require some time to cool below an electron emitting temperature and the condensers 42 of the filter system store a substantial amount of current, the telephone system would still be "alive" for an appreciable interval after contacts 63 and 65 on switch 64 open. This is undesirable and sometimes annoying and is prevented by completing the circuit from telephone 2 to ground through contacts 57 and 58 on relay 64. By the use of these contacts, however, the telephone circuit is opened immediately when switch 64 is thrown into "off" position, thereby making the telephones "dead" immediately.

The method of reducing the voltage applied to the heater elements of the tubes comprising an impedance element 25 in series with the primary winding 24 of the primary transformer is preferred because of its low cost and the fact that it may be employed with transformers of conventional design. However, there are other methods of obtaining the same result, two of which are disclosed in the detail diagrams of Figs. 2 and 3, in which all parts corresponding to those in Fig. 1 bear the same reference numerals with the suffix "a" in the case of Fig. 2 and suffix "b" in the case of Fig. 3.

In the modification shown in Fig. 2, the primary winding 24a is supplemented by an additional winding 68 connected in series therewith, and the relay 36a, in addition to the armature 59a and front contact 60a, is provided with a back contact 69. The portion 24a of the primary winding constitutes the usual or working winding and is connected directly across the supply circuit through contact 60a and armature 59a when the relay 36 is actuated. However, when relay 36 is released, as shown in Fig. 2, supplementary winding 68 is connected in series with the winding 24a across the source of supply through the back contact 69 and armature 59a. Obviously if the transformer is so designed that the secondary winding 26a delivers normal heating current to the heater elements of the amplifier tubes when the winding 24a is connected directly across the source of supply, then when the additional wind-

ing 68 is connected in series with winding 24a the potential developed in the winding 26a will be reduced in degree proportional to the increase in the number of turns in the primary winding. 5 Therefore, by suitably proportioning the winding 68 with reference to the winding 24a, the potential developed in the winding 26a may be reduced to any desired value when the extra winding 68 is cut in. Since the winding 68 would 10 never be required to carry a very heavy current, it can be made of much finer wire than the winding 24a.

In the modification shown in Fig. 3, the primary winding 24b is permanently connected to 15 the source of supply and the potential delivered to the heater elements of the tubes over conductors 27b and 28b is reduced by connecting those leads across only a portion of winding 26b when the system is idle. To this end, the relay 20 26b is provided with a back contact 69b which is connected to a tap 70 on the winding 26b, the front contact 60b of relay 36b is connected to the end of winding 26b and the armature 59b of relay 36b is connected to the end of conductor 25 27b. It will be readily apparent that with this arrangement when relay 36b is released the conductors 27b and 28b leading to the heater elements of the amplifier tubes will be connected across only a portion of winding 26b, thereby 30 reducing the potential applied to the heater elements to a value sufficient to maintain the associated cathodes at the desired temperature slightly below that at which they emit electrons. Except for the changes noted, the modified circuit 35 shown in Fig. 3 corresponds exactly to the circuit of Fig. 1.

It will be apparent in the circuits shown in Fig. 1 and the modifications shown in Figs. 2 and 3 that the cathodes of the tubes will be preheated 40 during idle periods without undue wastage of current since no current will be drawn from the high potential secondary winding 29 or the cathode filament heating winding 33 and, except for slight losses in the transformer and in the impedance element 25 (in the modification of Fig. 45 1) no electrical energy is consumed except that which is actually used to preheat the heater elements.

It will also be apparent that I have provided 50 an intercommunicating telephone system adapted to be completely energized from a source of alternating current which system is rendered instantly active by closing the control switch and 55 is rendered inactive instantly in response to opening of the control switch; and in which the direction of transmission may be reversed at will through the medium of a relay actuated by current from the rectifier system that supplies current to the anodes of the amplifier without introducing objectionable noises and without producing serious variations in the potential applied to the anodes of the amplifier tubes.

It will be understood that the circuit diagrams 65 illustrating the invention are highly schematic and that many refinements may be introduced in the schematic circuit shown without departing from the invention. For instance, the relay 36 might be eliminated and contacts provided directly on the control switch 64 corresponding to the various contacts shown on relay 36 for performing the same functions. Likewise if the layout of the circuit permits, the relay 44 may be eliminated and its functions performed by contacts corresponding to the relay contacts but ac-

tuated mechanically by the switch 48. It is to be understood that the speakers 1 and 2 may be located at widely separated points and both widely separated from the amplifier, current supply apparatus and relays, or the circuits and apparatus relating to the preheating of the amplifier cathodes and control of the rectifier filament circuit may be incorporated in a single box or cabinet. 5

Furthermore, it will be apparent to those skilled 10 in the art that my method of preheating the cathodes of tubes is in no sense limited to an intercommunicating telephone system, or to an audio frequency amplifier. Thus my method of 15 preheating heater-type cathodes is equally applicable to and has a wide field of use in radio broadcast receivers, which may include oscillator, detector, and radio frequency amplifying tubes in addition to audio frequency amplifier tubes. In brief, my method of preheating is applicable to 20 any vacuous tube device employing one or more heater-type tubes, and a hot cathode rectifier for supplying anode potential to the tubes.

I claim:

1. A vacuum tube device including a work circuit containing a working vacuum tube having an anode, an indirectly heated cathode and a heater element for the cathode; and a power supply circuit for said work circuit containing a rectifying vacuum tube having a directly heated 30 cathode, a power transformer having a primary winding adapted to be connected to a source of constant potential alternating current, a secondary winding connected to said heater element of said working vacuum tube for supplying heating current thereto, a secondary winding for supplying heating current to said rectifier cathode, and still another secondary winding for supplying high potential current through said rectifier tube to the anode of said working tube; 40 in combination with means for energizing and deenergizing said working circuit and preconditioning it for instant use, comprising current limiting means normally connected in the primary circuit of said power transformer for limiting the potential delivered by said first mentioned secondary winding to said heater element to a subnormal value, and a power control switch means for simultaneously applying the full potential of said source of said alternating current 45 to said primary winding and connecting said rectifier filament to its associated secondary winding. 50

2. Vacuum tube apparatus comprising a work circuit containing a working vacuum tube having an anode, an indirectly heated cathode and a heater element for said cathode, in combination with an energizing circuit for said vacuum tube, said energizing circuit comprising a vacuum tube rectifier having a filamentary cathode, a power 60 transformer having a primary winding, a first secondary winding connected to said heater element, a second secondary winding for supplying heating current to said rectifier filament, and a third secondary winding connected through said rectifier to the anode of said working tube, a source of alternating current of constant potential for energizing the primary winding of said transformer, means for varying the potentials induced in the secondary windings of said transformer between a high and a low value, control means operable between two positions for conditioning said potential varying means to develop high potential in said secondary windings and connect said second secondary winding to said 70 75 80 85 90 95 100

rectifier filament in one position and for conditioning said potential varying means to develop a low potential in said secondary windings and disconnect said second secondary winding from 5 said rectifier filament in its other position of operation.

3. In combination, a work circuit containing a vacuum tube having an anode, an indirectly heated cathode and a heater element for said cathode; 10 an energizing circuit for said vacuum tube, said energizing circuit comprising a vacuum tube rectifier having a filamentary cathode, a power transformer having a primary winding, a first secondary winding connected to said heater element 15 of said working tube, a second secondary winding for supplying heating current to said rectifier filament, and a third secondary winding connected through said rectifier to the anode of said working tube, a source of alternating 20 current of constant potential for energizing the primary winding of said transformer, voltage varying means for varying the potential applied from said first secondary winding to said heater element, means for connecting and disconnecting 25 said rectifier filament to said second secondary winding, and a single control means for simultaneously conditioning said voltage varying means to apply full potential to said heater element and connect said rectifier filament to said 30 secondary winding, or condition said voltage varying means to apply reduced potential to said heater element and disconnect said rectifier filament from said second secondary winding at will.

4. Apparatus as described in claim 2, in which 35 said means for varying the potentials induced in the secondary windings of said transformer between a high and a low value comprises an impedance element connected in series with the primary winding of said transformer with contact means for shorting out said impedance element, other contact means for connecting said secondary winding to said rectifier filament, and a single means for actuating both said contact means.

5. Vacuum tube apparatus comprising a work circuit, containing a working vacuum tube having an anode, an indirectly heated cathode and a heater element for said cathode, in combination with an energizing circuit for said working 40 vacuum tube, said energizing circuit comprising a vacuum tube rectifier having a filamentary cathode, a power transformer having a tapped primary winding, a first secondary winding connected to said heater element, a second secondary winding for supplying heating current to 45 said rectifier filament, and a third secondary winding connected through said rectifier to the anode of said working tube for supplying space current thereto, a source of alternating current 50 of constant potential for energizing the primary winding of said transformer, control means for energizing and de-energizing said apparatus comprising a multi-blade switching device operable into two positions and adapted to connect 55 said source across the full primary winding and open said rectifier filament circuit in one position and connect said source directly across a tapped portion of said transformer primary winding and

complete said rectifier filament circuit in the other position.

6. Vacuum tube apparatus comprising in combination a work circuit containing a working vacuum tube having an anode, an indirectly heated anode and a heater element for the cathode; an energizing circuit for said vacuum tube comprising a vacuum tube rectifier having a filamentary cathode, a power transformer having a primary winding, a tapped secondary winding 10 adapted to be connected to said heater element of said working tube, a second secondary winding for supplying heating current to said rectifier filament and a third secondary winding connected through said rectifier to the anode of 15 said working tube for supplying space current thereto, a source of alternating current of constant potential connected to the primary winding of said transformer for energizing the transformer, control means operable between two positions and comprising a plurality of sets of contacts for simultaneously connecting said heater element across a tapped portion of said first secondary winding and disconnecting said rectifier filament from said second secondary winding 20 in one position of operation and connecting said heater element directly across said first secondary winding and connecting said cathode filament to said second secondary winding in the other position.

7. In an intercommunicating telephone system, a pair of telephones, a vacuum tube amplifier connecting said telephones for receiving and amplifying voice currents generated by one telephone and applying them to the other telephone, 35 said amplifier containing vacuum tubes having anodes, grids, and heater type cathodes of considerable mass, whereby they heat and cool slowly, power supply means for energizing said amplifier from a source of alternating current, said 40 means including a rectifier and filter for supplying direct current to the anodes of the tubes, the filter containing condensers storing sufficient electricity to energize the tube anodes for a substantial interval after current supply thereto 45 from said rectifier has been cut off, said means also including a transformer for supplying current to heat said cathodes, energizing switch means for said system comprising a member operable into "on" and "off" positions and having a plurality of sets of contacts operable in response to movement of said member, some of 50 said contacts completing circuits to supply rectified current to said filter and full heating current to said cathodes when said member is in "on" 55 position and to interrupt the supply of rectified current to said filter and diminish the heating current to said cathodes when the said member is in "off" position, and others of said contacts completing voice current connection between said 60 telephones through said amplifier when said member is in "on" position and breaking said voice current connection when said member is in "off" position, whereby movement of said member into "off" position renders said telephones inoperative instantly regardless of lag in the shut-down of said amplifier.

PAUL BAKER.
